his Attorney.

UNITED STATES PATENT OFFICE.

CHARLES A. PSILANDER, OF EASTON, PENNSYLVANIA, ASSIGNOR TO WILLIAM WHARTON JR. & COMPANY, INCORPORATED, OF EASTON, PENNSYLVANIA, A CORPORATION OF PENNSYLVANIA.

CAST UNDERFRAME FOR CARS.

1,367,429.

Specification of Letters Patent.

Patented Feb. 1, 1921.

Application filed July 14, 1919. Serial No. 310,542.

To all whom it may concern:

Be it known that I, CHARLES A. PSILANDER, a citizen of the United States, residing at Easton, in the county of Northampton 5 and State of Pennsylvania, have invented certain new and useful Improvements in Cast Underframes for Cars, of which the following is a specification.

This invention relates to cast steel under-10 frames for cars.

One of the principal objects is to provide an exceptionally light yet strong casting especially adapted to support the bottom plate and sides of mining cars.

15 Another object is to provide an integral casting of thin cross section constituted of electric steel.

Another object is to provide an under-20 frame of the character indicated in which all sections through the longitudinal and cross members are angle shape, the side members or sills having the horizontal legs of their angles turned toward the center of the frame, and the central longitudinal 25 members having the horizontal legs of their angles turned away from the center.

Another object is to provide an under-30 frame of the character indicated wholly devoid of projections and wherein provision is made for bolting or riveting the pedestals to the vertical legs of the side members.

Still another object of the invention is to provide in an underframe of the character stated, spring seats for the drawbar or draft 35 rigging.

Other objects as well as the nature, characteristic features and scope of the invention will more readily be understood from the following description taken in connection with the accompanying drawing, 40 wherein—

Figure 1 is a top view of a car under-frame embodying features of my invention.

Fig. 2 is a section on line 2—2 of Fig. 1. 45 Fig. 3 is an enlarged sectional view of one of the spring seats for the draft rigging.

As stated at the outset, and, as indicated in Fig. 2, the cross-sections are usually thin, being cast from electric steel. I am enabled 50 to do this without weakening the structure in any way by forming the longitudinal and cross members of angle shape.

The casting comprises the central longitudinal members 5, side members or sills 6,

the end members 7 and 8, and the intermediate cross members 9. As before mentioned, 55 all of the members are of angle form in cross section as indicated in Figs. 2 and 3, the horizontal legs 10 of the side members being inwardly directed, that is to say, toward the center of the casting, and the center sills or longitudinal members having their angular portions 11 directed toward the side sills. Similarly the cross members, 60 including the end sills, have their horizontal faces directed inwardly. The top of the frame is rectangular without any projections whatever. There are no holes or seats for bolsters, but provision is made for bolting the pedestals to the vertical legs 12 of 70 the side sills.

The end cross members 7 and 8 provide 75 spring seats for the draft rigging, as illustrated in Figs. 1 and 3. Those portions of the end sills lying between the center longitudinal members have drawbar openings 13, and intermediate the members 7 and 8 is an integral flanged member 14 with a similar opening 15. Flanged bushings 16 and 17 are 80 accommodated, respectively in the openings in the members 8 and 14, and are under the compression of a coiled spring 18. The element 19 of the draft rigging is movable in the bushing 17 and is secured to the bushing 16 by a key 20. It will be noted that the 85 inside end sill or tension member 8 is reinforced by horizontal web 21 flush with the top of the center longitudinal members.

Having described the nature and objects 90 of the invention, I claim:—

1. An underframe for cars, consisting of 95 a single casting having spaced center and longitudinal side members of angle shape in cross sections with their horizontal faces in substantially the same plane, the horizontal faces of the side members being directed toward the center of the casting and the horizontal faces of the center members being directed in opposite directions and toward the adjacent side member.

2. An underframe for cars, consisting of 100 an integral casting having side and end members, spaced center members, and cross members between the center members adjacent the end members, the said cross members being formed to provide spaced draft rigging seats.

3. An underframe for cars, consisting of

an integral casting having side and end members, spaced center members, and cross members between the center members adjacent the end members, the said cross members being formed to provide spaced draft rigging seats, the end member in line with the cross members being formed to provide a guide for the drawbar.

4. An integral underframe for cars hav-

ing angle-form side members, angle-form spaced center members, angle-form cross members between the center members adjacent each end of the frame, the vertical webs of such cross members being formed to provide draft rigging seats.

In testimony whereof I affix my signature.

CHARLES A. PSILANDER.
